UNITED STATES PATENT OFFICE

141,168

DESIGN FOR A COMBINED SHOULDER AND HEAD REST FOR THROAT OPERATIONS OR THE LIKE

William L. Mermis, Youngstown, Ohio

Application July 31, 1944, Serial No. 114,662

Term of patent 14 years

(Cl. D83—1)

To all whom it may concern:

Be it known that I, William L. Mermis, a citizen of the United States, residing at the city of Youngstown, county of Mahoning, State of Ohio, have invented a new, original, and ornamental Design for a Combined Shoulder and Head Rest for Throat Operations or the like, of which the following is a specification, reference being made to the accompanying drawing, forming a part thereof. Figure 1 is a perspective view of the combined shoulder and head rest for throat

operations or the like embodying my new design, with the chin strap thereof shown in upwardly disposed position, and Figure 2 is a perspective view with the chin strap in downwardly disposed position.

I claim:

The ornamental design for a combined shoulder and head rest for throat operations or the like, substantially as shown.

WILLIAM L. MERMIS.
